FOUNTAIN BRUSH

Raymond B. Maestas, Los Angeles, Calif.

Application July 26, 1949, Serial No. 106,896

9 Claims. (Cl. 15—129)

1

This invention relates to washing devices and more particularly to a hand held device which is controllable to deliver either a solution of water and a cleaning compound or a clear water for rinsing the article cleaned.

The device of the present invention is one which may be used to thoroughly clean any article desired, and as the delivery therefrom of the cleaning solution or clear rinsing water is controlled by means of a single actuator, the operation of the device is extremely simple. The cleaning action of the device is further enhanced by the provision of bristle elements through which the cleaning solution is delivered during the washing operation. Thus the article is cleaned both by the action of the solution and the scrubbing action of the bristles as the latter are moved over the article.

In the illustrated embodiment of the present invention the device includes an outer container having a handle element through which a supply of water is delivered into the container. The container is formed with a perforated wall portion through which the water is delivered into the bristles during the rinsing operation. A smaller or inner vessel mounted within the container is intended to hold a supply of the cleaning compound which may consist of powdered soap, granular detergent, or the like, which is to be intermixed with or dissolved in the water supplied to the device during the cleaning operation. To this end, means are provided for diverting the flow of water through the apertured wall portion of the outer container into the vessel to intermix with the compound held thereby.

The solution of water and cleaning compound is discharged from the inner vessel through an apertured plate closing the opened end of the vessel and which is movable relative to the apertured wall portion of the outer container. Water is passed into the vessel through an apertured wall which is engaged by a second apertured plate which is movable relative to the apertured wall of the vessel. The relative movement between the plate and the wall is brought about by means of an actuator mounted on the exterior of the device which when operated also produces relative movement between the first plate and the apertured wall of the outer container.

The apertures in the wall portion of the outer container and the relatively movable plate engaged thereby are such relative to the spacing and arrangement of the apertures formed in the

2

wall of the inner vessel and the plate engaged thereby that when the first mentioned apertures are in alignment or in registry the second named apertures are out of registry. Thus in one position of the actuator water delivered into the outer container will flow into the vessel to intermix with the compound held thereby and thence be discharged into the bristles of the device. By operation of the single actuator communication between the interiors of the vessel and container is destroyed and water delivered into the outer container flows directly into the bristles of the device.

As it is not necessary to have a high rate of flow of the water during the cleaning operation, as a high rate of flow would unnecessarily dissipate the cleaning compound, valve means are carried by the handle element for restricting the flow of water into the device during the cleaning operation. When the article cleaned is to be rinsed the valve may be operated to permit a large volume flow through the container to insure a goodly supply of clear water for the rinsing operation.

Other features and advantages of the device of the present invention will be hereinafter apparent from the following description, particularly when taken in connection with the accompanying drawing, in which:

Figure 1 is a vertical sectional view of the device of the present invention;

Figure 2 is a section taken along line 2—2 of Figure 1;

Figure 3 is a section taken along line 3—3 of Figure 1; and

Figure 4 is a section taken along line 4—4 of Figure 1.

The washing device of the present invention, referring now to the drawing and more particularly to Figure 1 thereof, comprises a body member 10 which includes a pair of substantially cylindrical open ended, nested enclosures 11 and 12 integrally formed with the open ends thereof oppositely facing. The container formed by the enclosure 11 includes a cylindrical wall element 13 and a transversely extending annular wall element 14. The vessel formed by the enclosure 12 includes a cylindrical wall element 15 and a circular wall element 16. The open end of the container 11 is closed by a closure 17 having an annular depending flange 18 threadedly engaging the cylindrical wall 13 adjacent the open end of the container. To seal the jointure between the wall 13 and the closure 17 a gasket 19 of some suitable resilient material is

preferably interposed between the closure 17 and the end face of the wall 13.

The closure 17 is formed with a centrally located boss 21 having an opening therethrough for passing the reduced end of a spindle 22. The lower end of the spindle is passed through an opening formed in a centrally located boss 23 carried by the wall element 16 and the free end thereof extending beyond the boss 23 is rigidly secured by any conventional means such as by a brazing operation, in a centrally located aperture formed in a plate 24 facewisely engaging the inner surface of the wall element 16. The reduced end of the spindle 22 projects upwardly beyond the boss 21 and has secured thereto an actuator knob 25, the actuator knob being fixed to the spindle by a conventional set screw as shown.

The wall of the opening through the boss 21 is formed with a groove for receiving an annular gasket 26 which seals the annular space between the reduced end of the spindle 22 and the opening. A similar gasket 27 is seated in a groove formed in the wall of the opening in the boss 23 and seals the passage of the spindle through the opening in this boss.

As the end of the spindle 22 is secured in the opening of the plate 24, rotation of the actuating knob 25 will rotate the plate 24 relative to the wall element 16. The wall element 16 is formed with a plurality of radially extending, spaced apertures 28 which are adapted to be brought into registry with similarly spaced apertures 29 formed in the plate 24 when the latter is rotatably moved by actuation of the knob 25.

Rigidly secured to the undersurface or exposed face of the plate 24 are a plurality of elongate arms 31 each formed at the free ends thereof with fingers 32 adapted to be received within openings 33 formed in a plate 34 of a diameter substantially equal to the inner diameter of the container 11. The plate 34 is held in facewise engagement with the annular wall element 14 by a bristle mounting board 35 detachably held to a ring 36 by means of headed studs 37 carried by the ring 36. The headed studs 37 may comprise bolts threaded into blind tapped openings formed in the ring 36. The studs 37 are passed downwardly through openings 38 formed in the mounting board 35, after which the mounting board is rotated to relatively move the bolts through slots 39 arcuately extending from the openings 38. As the head of the stud 37 is larger than the width of the slots 39, the mounting board 35 is detachably held against removal from the ring 36.

The ring 36 in turn is held to the body member 10 by means of a plurality of cam lugs 41 and 42. The lugs 41 are spacedly formed about the inner diameter of the ring 36 and are movable through the openings between the lugs 42 which are carried by the body member 10, after which the ring and the mounting board 35 carried thereby can be rotated to move the lugs 41 over the lugs 42. As the lugs 42 are formed with upwardly directed surfaces at the top thereof, as viewed in Figure 1, the camming action between these inclined surfaces and the undersurface of the lugs 41 will draw the ring up tightly against the undersurface of the flange of the body member 10. It should now be obvious that after the ring 36 has been locked to the lugs 42 of the body member 10, the mounting board 35 will hold the plate 34 in facewise engagement with the undersurface of the annular wall element 14.

The annular wall element 14 is formed with

a plurality of spaced, radially extending apertures 43 which in certain positions of the plate 34 register with apertures 44 formed in the latter. As the finger 32 of the arms 31 depending from the plate 24 are engaged in the openings 33 of the plate 34, rotation of the plate 24 will simultaneously bring about rotation of the plate 34. The openings 29 in the plate 24 are so spaced therein that as these apertures are moved into registry with the apertures 28 of the plate of the wall element 16 the apertures 44 of the plate 34 are moved out of registry with the openings 43. It should be noted that the mounting board 35 is formed with a plurality of relatively large apertures 45 and that the upper face of this board is centrally relieved to form a circular chamber 46 intermediate the plate 34 and the mounting board 35.

It will now be understood that liquid delivered into the container 11 when the apertures 43 and 44 are in alignment will flow through the passage formed by the aligned apertures 43 and 44 into the chamber 46 and thence be discharged through the apertures 45 of the bristle mounting board 35.

Liquid is introduced into the container 11 through a handle element 47 which comprises a tubular element threadedly mounted in a tapped opening formed in a boss 48 carried by the cylindrical wall element 13 of the body member 10. The free or outer end of the handle element 47 is formed with a conventional female connector member 49 for receiving the male coupling member of a flexible hose element 51. A valve 52 rotatably mounted in the handle element 47 controls the flow of liquid through the handle element and is actuated by an operating knob 53. The valve 52 in one position thereof permits free flow of a liquid through the handle element 47 and by appropriate manipulation of the operating knob 53 selectively restricts the flow until it is moved to a position in which liquid will flow through the handle element 47.

In the use of the device of the present invention the vessel formed by the enclosure 12 is intended to receive cleaning materials such as granulated soap, detergents, and other like compounds, which are to be intermixed with liquid such as water introduced into the device through the handle element 47. When it is desired to wash an article the actuator knob 25 is used to so rotatably move the plate 24 as to bring the apertures 28 and 29 into registry to afford communication from the interior of the container 11 to the interior of the vessel 12. It will be remembered that when the apertures 28 and 29 are aligned or in registry, apertures 43 and 44 of the wall element 13 and plate 34, respectively, are out of registry. Thus water introduced into the container 11 is forced to flow into the passages formed by the aligned apertures 28 and 29 to be intermixed with the cleaning compounds held by the vessel 12, after which they are discharged through the apertures 44 formed in the central portion of the plate 34 extending across the open end of the vessel 12.

The solution of cleaning compound and water passed through the apertures 44 enters the chamber 46 and is then discharged through the openings 45 through the bristles 54 onto the article being cleaned. After the article has been thoroughly cleaned by the action of the bristles 54 and the solution of cleaning compound and water, the article may be rinsed by actuating the knob 25 to move the plate 24 to the position in which the

apertures 28 and 29 are no longer aligned, which closes the flow of water into the interior of the vessel 12. As the plate 34 is connected to the plate 24 for rotation therewith by the arms 31, movement of the plate 24 brings about rotation of the plate 34 to bring apertures 43 and 44 into alignment and water flows therethrough and is discharged into the bristles 54.

As water can now no longer flow through the vessel 12, the water discharged through the bristles 54 contains no cleaning compound and consequently the article can be quickly rinsed by the clear water discharged through the bristles. It might be mentioned here that during the cleaning operation the flow of water into the vessel 12 can be lessened by proper manipulation of the valve operator 53, as in this operation it is not necessary that a larger amount of water be discharged from the device. This is not done of course in the rinsing operation for here a large amount of clear water is necessary to properly rinse the article cleaned so that during the rinsing operation the valve 52 should be so positioned as to allow the maximum flow of water into the device.

When it is desired to replenish the supply of cleaning compound held by the vessel 12, the ring 36 is rotated to move the cam lugs 41 and 42 out of engagement, after which the ring is coaxially moved away from the body member 10 to expose the plate 34. After the plate 34 has been lifted from the wall element 14, the interior of the vessel 12 is exposed and can be quite easily again filled with the cleaning compound being used. After the supply of cleaning compound has been replenished the plate 34 can be again placed in position on the plate 14 and to assure alignment of the openings 33 with the fingers 32 the plate 34 is preferably formed with a cylindrical thickened portion 55 at the center thereof which forms an indexing means for properly locating the plate 34 to insure easy and ready insertion of the fingers 32 into the openings 33. With the plate 34 properly located, the ring 36 can be again mounted to the flange by merely rotating the same a distance sufficient to again bring the cam lugs 41 and 42 into engagement.

It should now be understood that the device of the present invention provides a means for supplying to the bristles 54 a solution of a cleaning compound and water or clear water as desired. The means for selecting either a solution of cleaning compound and water or clear water is but a single actuator, which obviates any confusion where two separate actuators are used to control the spray discharged from the device. As all of the apertured members of the device are easily accessible, there is no danger of the device becoming clogged with foreign matter during use. The apertures 28 and 29 can be quite easily cleaned of foreign matter by removal of the closure 17, and apertures 44 and 43 by removal of the bristle mounting board 35.

Although the now preferred embodiment of the present invention has been shown and disclosed herein, it is to be understood that the invention is not necessarily limited thereto but is susceptible to changes in form and detail within the scope of the appended claims.

I claim:

1. A washing device of the type described, comprising: a pair of substantially cylindrical, open ended, nested enclosures, the wall of the inner enclosure adjacent the open end thereof being integrally formed with the closed end of the outer enclosure whereby the open ends of said enclos-

ures are oppositely facing; the transverse end closing wall of each enclosure being formed with a plurality of spaced apertures; means for closing the open end of the outer enclosure; an apertured plate facewisely engaging the apertured wall of the inner enclosure; a second apertured plate facewisely engaging the apertured wall of said outer enclosure; means carried by said closing means for simultaneously rotating both of said plates relative to the apertured walls engaged thereby, the apertures of said first plate and the wall engaged thereby being so spaced and arranged relative to the spacing and arrangement of the apertures of said second plate and the wall engaged thereby that the last named apertures are out of registry when the first named apertures are in registry; and means for supplying a liquid to the interior of said outer enclosure, the registry of the apertures of said first plate and the wall engaged thereby establishing communication between the interiors of said enclosures whereby water delivered into said outer enclosure flows into the inner enclosure to intermix with a supply of a cleaning material held thereby and the resulting solution is discharged through the apertures of said second plate formed in the portion of the same extending across the open end of said inner enclosure, the registry of the apertures in the outer portion of said second plate and the wall of the outer enclosure engaged thereby, closing communication between the interiors of said enclosures and affording communication between the interior of said outer enclosure and the exterior thereof; and a perforated brush detachably mounted to said outer enclosure for receiving the discharge through said the second plate and holding the latter in engagement with the apertured wall of said outer enclosure.

2. A washing device of the type described, comprising: a container; means for supplying water to the interior of said container; a vessel mounted in said container; a plate engaging the one wall of said vessel, said plate being formed with a plurality of apertures and movable relative to said vessel to selectively bring the apertures therein into and out of registry with a plurality of apertures formed in the wall of said vessel engaged thereby to afford variable communication between the interior of said container and vessel; a second plate having a plurality of apertures formed therein; said last named plate being movable relative to an apertured wall portion of said container with which it facewisely engages whereby the apertures of said second plate can be selectively brought into and out of registry with the apertures of said wall portion thereby affording variable communication between the interior and exterior of said container; means for producing a relative movement between said first plate and the apertured wall of said vessel and between said second plate and the apertured wall portion of said container, the apertures of said first plate and the wall engaged thereby being so spaced and arranged relative to the spacing and arrangement of the apertures of said second plate and wall engaged thereby that the last named apertures are out of registry when the first named apertures are in registry; and means for holding said second plate in facewise engagement with said apertured wall portion of the container; said means including a brush, comprising a plurality of bristles and a mounting means therefor substantially coextensive with said second plate.

3. A washing device of the type described, comprising: a container having an opening centrally formed in one wall thereof; said wall being formed with a plurality of apertures arranged about said opening; means for supplying water to the interior of said container; an open-ended vessel mounted in the opening formed in the one wall of said container and closing the same; a plate engaging one wall of said vessel, said plate being formed with a plurality of apertures and movable relative to said vessel to selectively bring the apertures therein into and out of registry with a plurality of apertures formed in the wall of said vessel engaged thereby to afford variable communication between the interior of said container and vessel; a second plate having a plurality of apertures formed therein facewisely engaging the apertured wall of said container and transversely extending across the open end of said vessel; said last named plate being movable relative to said apertured wall of said container whereby the apertures of said second plate can be selectively brought into and out of registry with the apertures of said wall, thereby affording variable communication between the interior and exterior of said container; and means for producing a relative movement between said first plate and the apertured wall of said vessel and between said second plate and the apertured wall portion of said container, the apertures of said first plate and the wall engaged thereby being so spaced and arranged relative to the spacing and arrangement of the apertures of said second plate and wall engaged thereby that the last named apertures are out of registry when the first named apertures are in registry.

4. A washing device of the type described, comprising: a container; means for supplying water to the interior of said container; a vessel mounted in said container; a plate engaging the one wall of said vessel, said plate being formed with a plurality of apertures and movable relative to said vessel to selectively bring the apertures therein into and out of registry with a plurality of apertures formed in the wall of said vessel engaged thereby to afford variable communication between the interior of said container and vessel; a second plate having a plurality of apertures formed therein; said last named plate being movable relative to an apertured wall portion of said container with which it facewisely engages whereby the apertures of said second plate can be selectively brought into and out of registry with the apertures of said wall portion thereby affording variable communication between the interior and exterior of said container; and means for producing a relative movement between said first plate and the apertured wall of said vessel and between said second plate and the apertured wall portion of said container, the apertures of said first plate and the wall engaged thereby being so spaced and arranged relative to the spacing and arrangement of the apertures of said second plate and wall engaged thereby that the last named apertures are out of registry when the first named apertures are in registry.

5. A washing device of the type described, comprising: a container having an opening in an apertured wall portion thereof and open at the opposite end; a closure for said open end; a handle projecting from said container and having a passage leading from the one end thereof to the interior of said container; means carried at the end of said handle for attachment to a water supplying source; an open ended vessel centrally carried within said container for re-

ceiving material to be mixed with the water; said vessel closing the opening in said apertured wall portion and being provided with at least one apertured wall; an apertured plate held in facewise engagement with the apertured wall of said vessel and movable relative thereto; a second apertured plate extending across the open end of said vessel and facewisely engaging the apertured wall portion of said container; said wall portion being movable relative to said second plate; manually operable means for moving said first plate relative to the apertured wall of said vessel; and means for moving said apertured wall portion of said container relative to said second plate upon operation of said manually operable means; the apertures in said first plate and wall being so spaced as to be in registry in one relative position of said vessel and first plate, the apertures in said second plate and wall portion being so spaced as to be out of registry in said position but movable into registry upon operation of said manually operable means to move said vessel and plate to a relative position in which the apertures therein are out of registry.

6. A washing device of the type described, comprising: a container having an opening in an apertured wall portion thereof; a handle projecting from said container and having a passage leading from the one end thereof to the interior of said container; means carried at the end of said handle for attachment to a water supplying source; an open ended vessel centrally carried within said container for receiving material to be mixed with the water; said vessel closing the opening in said apertured wall portion and being provided with at least one apertured wall; an apertured plate held in facewise engagement with the apertured wall of said vessel and movable relative thereto; an apertured second plate extending across the open end of said vessel and facewisely engaging the apertured wall portion of said container; said wall portion being movable relative to said second plate; manually operable means for moving said first plate relative to the apertured wall of said vessel and said apertured wall portion of said container relative to said second plate; the apertures in said first plate and the wall of said vessel being so spaced as to be in registry in one relative position of said vessel and first plate, the apertures in said second plate and wall portion being so spaced as to be out of registry in said position but movable into registry upon operation of said manually operable means to move said vessel and plate to a relative position in which the apertures therein are out of registry, registry of the apertures in said first plate and wall affording communication between the interiors of said vessel and container whereby water entering said container flows into said vessel to intermix with the material held thereby for discharge through the apertures of said second plate; and means for varying the flow of water into said container.

7. A washing device of the type described, comprising: a pair of substantially cylindrical, open ended, nested enclosures integrally formed with the open ends thereof oppositely facing; the transverse end closing wall of each enclosure being formed with a plurality of spaced apertures; means for closing the open end of the outer enclosure; an apertured plate facewisely engaging the apertured wall of the inner enclosure; a second apertured plate facewisely engaging the apertured wall of said outer enclosure; means for simultaneously rotating both of said plates relative to the apertured walls engaged thereby, the aper-

tures of said first plate and the wall engaged thereby being so spaced and arranged relative to the spacing and arrangement of the apertures of said second plate and the wall engaged thereby that the last named apertures are out of registry when the first named apertures are in registry; and means for supplying a liquid to the interior of said outer enclosure, the registry of the apertures of said first plate and the wall engaged thereby establishing communication between the interiors of said enclosures whereby water delivered into said outer enclosure flows into the inner enclosure to intermix with a cleaning material held thereby and the intermixed water and material is discharged through the apertures of said second plate formed in the portion of the second plate extending across the open end of said inner enclosure, the registry of the apertures of said second plate and the wall engaged thereby closing the communication between the interiors of said enclosures whereby water supplied to the interior of said outer enclosure is discharged therefrom through the aligned apertures of the said second plate and the wall engaged thereby.

8. A washing device of the type described, comprising: a pair of substantially cylindrical, open ended, nested enclosures, the open end of the inner enclosure being integrally formed with the closed end of said outer enclosure whereby the open ends of said enclosures face in opposite directions; the transverse end closing wall of each enclosure being formed with a plurality of spaced apertures; means for closing the open end of the outer enclosure; an apertured plate facewisely engaging the apertured wall of the inner enclosure; a second apertured plate facewisely engaging the apertured wall of said outer enclosure; means carried by the means closing the open end of said outer enclosure for simultaneously rotating both of said plates relative to the apertured walls engaged thereby, the apertures of said first plate and the wall engaged thereby being so spaced and arranged relative to the spacing and arrangement of the apertures of said second plate and the wall engaged thereby that the last named apertures are out of registry when the first named apertures are in registry; and means for supplying a liquid to the interior of said outer enclosure, the registry of the apertures of said first plate and the wall engaged thereby establishing communication between the interiors of said enclosures whereby water delivered into said outer enclosure flows into the inner enclosure to intermix with a supply of a cleaning material held thereby and the resulting solution is discharged through the apertures of said second plate formed in the central portion of the same extending across the open end of said inner enclosure, the registry of the apertures in the outer portion of said second plate and the wall of the outer enclosure engaged thereby closing the communication between the interiors of said enclosures and affording communication between the interior of said outer enclosure and the exterior thereof; and means for varying the amount of water supplied to said outer enclosure, whereby the rate of intermixing of said cleaning material and water can be varied.

55

is discharged through the apertures of said second plate formed in the portion of the second plate extending across the open end of said inner enclosure, the registry of the apertures in the higher portion of said second plate and the wall of the outer enclosure engaged thereby closing the communication between the interiors of said enclosures and affording communication between the interior of said outer enclosure and the exterior thereof.

9. A washing device of the type described, comprising: a pair of substantially cylindrical, open ended, nested enclosures integrally formed with the open ends thereof oppositely facing; the transverse end closing wall of each enclosure being formed with a plurality of spaced apertures; means for closing the open end of the outer enclosure; an apertured plate facewisely engaging the apertured wall of the inner enclosure; a second apertured plate facewisely engaging the apertured wall of said outer enclosure; means carried by said closing means for simultaneously rotating both of said plates relative to the apertured walls engaged thereby, the apertures of said first plate and the wall engaged thereby being so spaced and arranged relative to the spacing and arrangement of the apertures of said second plate and the wall engaged thereby that the last named apertures are out of registry when the first named apertures are in registry; means for supplying a liquid to the interior of said outer enclosure, the registry of the apertures of said first plate and the wall engaged thereby establishing communication between the interiors of said enclosures whereby water delivered into said outer enclosure flows into the inner enclosure to intermix with a supply of a cleaning material held thereby and the resulting solution is discharged through the apertures of said second plate formed in the central portion of the same extending across the open end of said inner enclosure, the registry of the apertures in the outer portion of said second plate and the wall of the outer enclosure engaged thereby closing the communication between the interiors of said enclosures and affording communication between the interior of said outer enclosure and the exterior thereof; and means for varying the amount of water supplied to said outer enclosure, whereby the rate of intermixing of said cleaning material and water can be varied.
